UNITED STATES PATENT OFFICE.

CHARLES L. HILDRETH, OF LOWELL, MASSACHUSETTS, ASSIGNOR TO THE
LOWELL MACHINE SHOP, OF SAME PLACE.

SEPARATOR MECHANISM FOR RING-SPINNING FRAMES.

SPECIFICATION forming part of Letters Patent No. 498,265, dated May 30, 1893.

Application filed February 10, 1893. Serial No. 461,727. (No model.)

To all whom it may concern:

Be it known that I, CHARLES L. HILDRETH, a citizen of the United States, residing at Lowell, in the county of Middlesex and State 5 of Massachusetts, have invented certain new and useful Improvements in Separator Mechanisms for Ring-Spinning Frames, of which the following is a specification, reference being had therein to the accompanying drawings.

10 This present invention relates to the devices that are employed in ring-spinning frames for supporting and operating the separators which sometimes are interposed between the spindles of such frames for the purpose of 15 restricting the "ballooning" of the yarns being spun, and for preventing the said yarns from striking against one another in consequence of such ballooning.

The main object of the invention is to provide a simple and practical improved arrangement and combination of supporting and operating devices whereby not only shall the separators be moved vertically simultaneously with the ring-rail, and also in the

25 same direction as the latter, but they shall be moved through a traverse of less extent than the ring-rail, so as to remain in proper position relatively to the various parts, the use of adjustable stops to determine the low-

30 est limit of the descent of the separators and of adjustable feet on the separator-rods to determine the highest point of the traverse of the separators thereby being rendered unnecessary; and wherein shall be embodied

35 improved means for enabling the traverse of the separators quickly and conveniently to be shifted higher or lower as desired with relation to the thread-board, spindles and ring-rail, without any resulting variation in the

40 extent of such traverse. The omission of the adjustable stops and adjustable feet secures a simplified and more reliable mechanism. Capacity for effecting a vertical shift or translation of the traverse of the sepa-

45 rators is highly desirable in a separator-mechanism in order that the requirements of the different conditions under which one and the same spinning-frame is used may be met properly, and also in order to enable the separator-mechanism to be fitted to the different sizes

50 of ring-spinning frames that are in use with-

out it being necessary to keep on hand a stock of various sizes or lengths. Separator-mechanisms of the same structural type as that to which the invention relates, as heretofore proposed to be built, usually have been devoid of capacity for the said vertical shift or translation. Where no provision for adjustment exists in the separator-operating devices, it becomes necessary for the maker 55 thereof to provide different lengths of separator-rods, or a like supply of different sizes or lengths of some other part or parts, in order to enable the traverse of the separators in a given spinning-frame to be varied by an 60 interchange of parts, and also in order to enable the separator-mechanism to be fitted to the different sizes of spinning-frames that are built.

Another object of the invention is to provide an improved form of the pivotal connections whereby the separator-rail is mounted at the upper ends of the separator-rods.

The invention consists, first, in certain features of improved construction and combination, embracing adjustable devices of an improved and novel character for enabling the traverse of the separators to be shifted or translated vertically as required, without the extent of such traverse being altered.

It consists, further, in an improved construction of the pivotal connections between the separator-rail and its supports.

The invention first will be described with reference to the accompanying drawings, in 85 which are represented the best embodiments thereof which so far have been devised, and then will be particularly pointed out and distinctly defined in the claims at the close of this specification.

In the drawings, Figure 1 is a view in front elevation showing a portion of a ring-spinning frame with the preferred embodiment of the invention applied thereto. Fig. 2 is a view in vertical section on the line 2-2 of 95 Fig. 1. Fig. 3 is a view in side elevation of certain of the parts which are represented in Fig. 1, and which are more immediately involved in the first portion of my invention. Fig. 4 is a view in plan of the parts which are 100 represented in Fig. 3 but with a portion thereof in section in order to show more clearly the

construction. Fig. 5 is a view in vertical section on the line 5—5 in Fig. 3. Fig. 6 is a view in vertical section on the line 6—6 in Fig. 3. Figs. 7 and 8 are views similar to Fig. 5 showing modifications. Fig. 9 is a view in rear elevation of the upper end of a separator-rod, the socket affixed thereon, part of the separator-rail, a separator, and a bracket mounted on the separator-rail. Fig. 10 is a view of the same parts, mostly in side elevation, but with the separator-rail in section. Fig. 11 is a view in side elevation of the socket which is affixed to the upper end of the separator-rod. Fig. 12 is a view in horizontal section on the plane indicated by the line 12—12 in Fig. 11. Fig. 13 is a view of the socket from the left-hand side in Fig. 11.

In Figs. 1 and 2, 1 is the roller-beam, 2 the thread-board hinged thereto as usual, 3 the finger-boards hinged as usual to the thread-boards, 4 the yarn-guides secured to the finger-boards, 5 the yarns passing from the yarn-guides 4 to the bobbin 6, through the travelers 7 on the rings 8 supported by the ring-rail 9, 10 the spindles on which the bobbins are mounted, 11 the spindle-rail, 12 the lower or guide-rail, 13 the lifting-rod for the ring-rail, 14 the shoe or foot at the lower end of the said rod, 16 the cross-shaft arm carrying the stud 15, the latter either acting directly upon the under face of the said shoe or foot or being provided with the roller 151, Fig. 6, which acts against the said face of the shoe or foot 14 and fits upon stud 15, it being held in place thereon by the thin-headed screw 152, the threaded part of which enters a threaded hole in the end of the stud.

At 17 is shown the cross-slot in the free end of the said cross-shaft arm 16 in which the said stud is adjustably mounted.

153 and 154 are, respectively, the washer and nut which are slipped upon the threaded end of the stud 15 and on the side of the arm 16 opposite that on which is located the roller 151, and by means whereof and the collar 155 on the stud the latter is clamped in the desired position of adjustment in the slot 17.

At 18 is shown the cross-shaft on which the said arm 16 is secured, the said cross-shaft 50 turning in bearings in brackets 19 (only one of which brackets is shown) and being caused to rock by usual means for the purpose of moving the ring-rail up and down, the cross-shaft being in practice usually provided with 55 an arm 181 on which is adjustably mounted a weight 182 for counterbalancing the parts which are operated by the arm 16.

All of the foregoing parts may be of any usual or preferred construction.

60 At 20 in Figs. 1 and 2 the separators are shown, and at 21 the separator-rail on which the separators are mounted.

At 22 is shown a rod by which the said rail is supported, the said rod, by preference, being tubular, and it being held in upright position by guides in a stand or bracket 23 which is secured by bolts 24, 24, and nuts

241, 241, to the rail 12. Provision is made as follows for actuating the rod 22 from the cross-shaft arm 16 simultaneously with the ring-rail and in the same direction but through a traverse of less extent, or for actuating similarly an equivalent support for the separator-rail. On the lower end of the rod 22 is affixed a shoe 25 having by preference the shape of an inverted T and formed with a flat under surface. The arm 16, see particularly Figs. 2, 3, 4 and 5, is formed with a vertical screw-threaded hole 26 therethrough at a point between the cross-shaft 18 and the stud 15, and through this hole is passed a screw-threaded stud or pin 27, the thread thereof fitting the hole, and the said stud or pin having nuts 28 thereon, one of the said nuts being above the portion of the arm 16 through which the stud or pin is passed, and the other nut being below such portion. By means of these nuts the stud or pin is locked after having been turned to adjust it transversely of the arm into desired position, the nuts being screwed up so as to bear against the opposite sides of the portion of the arm through which the stud or pin is passed. The stud or pin 27 is intended to support the separator-rod, or equivalent part or carrier for the separator-rail and the parts carried thereby, and for this purpose the lower face of the foot or shoe 25 may, if desired, rest upon the upper end of the stud or pin. I prefer, however, to interpose between the shoe and the upper end of the stud or pin a swiveling cap-piece 29, the same having a flattened upper surface to fit against the bottom face of the foot or shoe. The cap-piece may be applied variously to the upper end of the stud or pin. In the drawings it is shown formed with a concavity in its under face to receive the upper end of the stud or pin, which fits loosely into the cavity. Preferably, the upper end of the stud or pin is partly spherical and the concavity in the cap is correspondingly shaped.

In consequence of having the stud or pin 27 applied to the arm 16 at a point between the cross-shaft 18 and the stud 15, less movement will be communicated to the separator-rod (or equivalent carrier) and separators than to the lifting-rod. The distance from the axis of the cross-shaft at which the stud or pin is applied to the arm 16 is such as will secure the desired ratio between the extent of the up and down movement of the separator-rail and separators and that of the corresponding movement of the ring-rail and rings. In the drawings, as shown, the movement of the separator-rod and separators is intended to be about one-half as great as that of the lifting-rod and ring-rail. For the purpose of shifting vertically the traverse of the separators without varying such traverse in extent, the height to which the upper end of the stud or pin 27 extends above the upper surface of arm 16 is varied by effecting suitable rotation of the stud or pin in the hole 26. The stud

15 and stud or pin 27, it will be seen, are independently adjustable cross-wise of the arm 16, thereby enabling the traverse of the ring-rail to be shifted vertically as required, by 5 making proper adjustment of the stud 15, without such adjustment itself affecting the traverse of the separators, and also enabling the traverse of the separators to be independently adjusted or shifted vertically at any time relatively to the traverse of the ring-rail.

The devices shown in the present case for transmitting movement from the arm 16 to the separator-rail are extremely practical and simple. They are also comparatively inexpensive, and, inasmuch as all desirable lengths 15 of screw-threaded pins like that shown in the drawings are commonly kept in stock by manufacturers for various purposes, a longer or shorter pin could be substituted for another 20 at almost no expense. Repairs may be readily and cheaply made.

In practice one or both of the nuts 28 and 28 which are placed on the stud or pin 27 for the purpose of locking the same in adjusted 25 position may be omitted. The hole in the arm 16 through which the stud or pin 27 passes, instead of being provided with an internal screw-thread into which the external thread of the stud or pin will take, as hereinbefore described, 30 may be plain, as in Fig. 7. In this case the stud or pin will be held in desired position on the arm 16 by the nuts 28 and 28, and adjustment of the stud or pin in the direction of its length may be effected by rotating the nuts thereon. 35 The construction may be further modified by omitting the nut 28 which is placed underneath the arm 16, as shown in Fig. 8, thus leaving the nut 28 which is located on the upper side of the arm to sustain the stud or pin in 40 position. For the purpose of pivotally supporting the separator-rail upon the separator-rods, I fit upon the upper end of each of the separator-rods a socket or support 30, see Figs. 9 to 13, which is held in place by means 45 of a clamping screw 31 that passes through a threaded hole in the socket or support and takes bearing by its end against the side of the separator-rod, the upper part 32 of the socket or support having therein a hole 33 50 which receives a pin 37 projecting from a bracket 34 that is affixed to the separator-rail. The said bracket 34 is formed with a lip 341 that fits against one of the edges of the separator-rail to keep it from turning on the separator-rail, and it is held to the latter by means 55 of the screw 35. It is formed with an ear or lug 36 that carries the pin 37. The part 32 of the socket or support 30 is formed at its front with a rest 38 serving as a support for the 60 separator-rail when it has been turned forward into the working position thereof and it is formed on its top with a similar rest 39 serving as a support for the separator-rail when it has been turned into the idle position 65 thereof, the part of the said socket intermediate the rests being so formed as not to interfere with the free movement of the sepa-

rator-rail upon its pivots in being turned from one of its positions to the other. The rests 38 and 39 preferably are formed, as shown, 70 as plane surfaces disposed eccentrically with reference to the path of movement of the separator-rail and against which the rear surface of the separator-rail takes a bearing. If desired, the rear side of bracket 34 might be arranged to take a bearing against the rests 38 and 39, and I consider this to be the equivalent of the arrangement shown and above described.

I claim as my invention—

1. The combination with the separators, the separator-rail, the separator-rod, and the foot or shoe at the lower end of said rod, of the arm 16, the screw-threaded stud or pin passed therethrough, and the swiveling cap on the 85 upper end of the pin and acting against the face of the foot or shoe of the separator-rod, substantially as described.

2. The combination with the separators, the separator-rail, the separator-rod, and the foot or shoe at the lower end of said rod, of the arm 16, the screw-threaded stud or pin passed therethrough, a nut or nuts for securing the said pin in adjusted position on the said arm, and the swiveling cap on the upper end of the 95 pin and acting against the face of the foot or shoe of the separator-rod substantially as described.

3. The combination with the separators, the separator-rail, and the separator-rod, having 100 a foot or shoe at the lower end thereof, of the arm 16, the screw-threaded stud or pin passed therethrough, nuts on said pin above and below the portion of the arm through which the same is passed for securing it in adjusted position, and the swiveling cap on the upper 105 end of the said pin and acting against the face of the foot or shoe on the separator-rod, substantially as described.

4. The combination with the ring-rail, the lifting-rod, the arm 16, means for operating the lifting-rod from the said arm 16, the separators, the separator-rail, and the separator-rod having a foot or shoe at the lower end thereof, of the screw-threaded stud or pin 115 passed vertically through the said arm 16 at a point intermediate the axis on which the same turns and the point at which power is transmitted to the lifting-rod, substantially as described.

5. The combination with the ring-rail, the lifting-rod, the arm 16, means for operating the lifting-rod from the said arm 16, the separators, the separator-rail, and the separator-rod having a foot or shoe at the lower end 125 thereof, of the screw-threaded stud or pin passed vertically through the said arm 16 at a point intermediate the axis on which the same turns and the point at which power is transmitted to the lifting-rod, and a nut or 130 nuts whereby the said stud or pin is held in adjusted position, substantially as described.

6. The combination with the ring-rail, the lifting-rod, the arm 16, means for operating

the lifting-rod from the said arm 16, the separators, the separator-rail, and the separator-rod having a foot or shoe applied to the lower end thereof, of the screw-threaded stud or 5 pin passed through the said arm at a point intermediate the axis on which the same turns and the point at which power is transmitted to the lifting-rod, a nut or nuts whereby the said stud or pin is held in adjusted position, and the swiveling cap on the upper 10 end of the said stud or pin and acting against the lower end of the foot or shoe of the separator-rod, substantially as described.

7. The combination with the separators, the 15 separator-rail, and a bracket affixed to the separator-rail, of a support with which the said bracket is pivotally connected, the said support having the rests 38 and 39 against which the separator-rail takes bearing and

whereby the separator-rail is supported in its 20 working and idle positions, substantially as described.

8. The combination with the separators, the separator-rail, and a bracket affixed to the separator-rail, of a support with which the 25 said bracket is pivotally connected, the said support having the rests 38 and 39 constituted by plane surfaces disposed eccentrically with reference to the path of movement of the separator-rail and against which the rear 30 surface of the separator-rail takes bearing, substantially as described.

In testimony whereof I affix my signature in the presence of two witnesses.

CHAS. L. HILDRETH.
